(No Model.)

T. NORDENFELT.
ORDNANCE CARRIAGE.

No. 338,766.

Patented Mar. 30, 1886.

UNITED STATES PATENT OFFICE.

THORSTEN NORDENFELT, OF WESTMINSTER, ENGLAND.

ORDNANCE-CARRIAGE.

SPECIFICATION forming part of Letters Patent No. 338,766, dated March 30, 1886.

Application filed August 11, 1885. Serial No. 174,129. (No model.) Patented in England March 6, 1882, No. 1,072, and in France June 15, 1882, No. 149,619.

To all whom it may concern:

Be it known that I, THORSTEN NORDENFELT, a subject of the King of Sweden, residing at 53 Parliament Street, in the city of Westminster, (late of St. Swithin's Lane, in the city of London,) England, have invented certain new and useful Improvements in Carriages for Naval and Field Ordnance, (for which I have received Letters Patent in Great Britain, No. 1,072, dated March 6, 1882, and in France, No. 149,619, dated June 15, 1882,) of which the following is a specification.

The object of this improvement is to check the recoil from guns, and to carry them quickly back again to firing position with moderated rebound. To obtain this, I combine a spring with a hydraulic buffer. I put the spring or springs inside the hydraulic cylinder in such a way that they are acted upon direct by the hydraulic piston. The liquid in the cylinder is on both sides of the piston, and is during the action of the recoil forced from one side of the piston to the other through specially-made passages. These passages consist of grooves along the inner surface of the cylinder, and their combined sectional area may either be constant over the whole stroke or varying for the purpose of better regulating the fluctuation of pressure during the movement of the piston. As described, the variation of the area of the grooves is obtained by making them more or less deep or wide, or by increasing or diminishing their number at certain parts of the length of the cylinder. The action of this arrangement may readily be understood, as follows: When the shot is fired, the piston forces the liquid from one side to the other through the passages, and at the same time compresses the spring, thus taking up the recoil by the hydraulic action and by the spring combined. When the recoil is partly absorbed by the hydraulic resistance and partly stored up in the spring, the latter carries the piston back again with a rapidity moderated by the resistance of the liquid, and thus brings the gun again in firing position without any injurious shock to the carriage.

In order that my said invention may be most fully understood and readily carried into ef-

fect, I will proceed to describe the drawings 50 hereunto annexed.

In the drawings, Figure 1 is a side elevation, partly in section, of a gun upon a pivot-carriage to which my combined spring and hydraulic buffer is applied. Fig. 2 is a rear 55 elevation, and Fig. 3 is a plan of the same. Fig. 4 shows a longitudinal section, and Fig. 5 a transverse section, of the hydraulic cylinder.

The trunnions of the gun are carried upon a lever, *a*, of which the fulcrum is at *a'*, so that the lower end of the lever is drawn forward by the recoil. The lever *a* is here jointed to the piston-rod *b* of a piston, *c*. The piston-rod is surrounded by the spiral springs *d*, 65 and *e* is a disk through which the rod passes freely.

f is a cylinder in which the piston, the springs, and the disk are contained. The end cover of the cylinder *f* is secured to the gun-carriage by a bolt, *g*, on which the cylinder is able to rock slightly, to accommodate itself to the position of the lever *a*. At the front end of the cylinder *f* there is a gland containing a cupped leather, *f'*, to retain the oil or other 75 liquid with which the cylinder is filled.

*f*² *f*² are grooves within the cylinder to permit the oil or liquid to pass the piston. They become fewer and narrower as the fore end of the stroke of the piston is approached. 80

Other parts of the gun-carriage and the gun are clearly shown in the drawings, but they form no part of the invention secured to me by this patent.

Having thus described the nature of the 85 said invention and the manner of performing the same, I would have it understood that what I claim is—

1. The combination, with a gun-carriage, of a hydraulic cylinder and piston for controlling 90 the movement of the gun in recoiling and returning to the firing position, and the spring acting upon the piston to check the recoil and restore the gun to the firing position, substantially as and for the purpose set forth. 95

2. The combination, with a gun-carriage, of the grooved hydraulic cylinder and its piston for controlling the movement of the gun in

recoiling and returning to the firing position, and the spring within said cylinder and acting upon the piston for checking the recoil and restoring the gun to the firing position, substantially as and for the purpose set forth.

3. The combination, with a gun-carriage, of a hydraulic cylinder, its piston, and piston-rod, a spring within the cylinder and acting upon the piston, and the pivoted lever of the gun-

carriage connected at its lower end with the piston and at its upper end supporting the gun by its trunnions, substantially as and for the purpose set forth.

THORSTEN NORDENFELT.
